HOT SEAL COOLING MECHANISM

James D. Wells, Floral Park, N. Y., assignor to
 American Machine & Foundry Company, a corporation of New Jersey

Application January 2, 1942, Serial No. 425,419

4 Claims. (Cl. 93—2)

1

This invention relates to a wrapping machine and has particular reference to seal forming mechanism of a wrapping machine.

Most of the wrapping machines in present day use employ heat to seal the overlapped and folded ends of a heat sealable wrapping material such as wax paper or cellophane. The tendency has been to operate these machines at faster and faster rates of speed to reduce the wrapping cost per article. When this is done, long cooling belts heretofore employed for holding hot seals together until they have set have been rendered unsatisfactory because they absorb considerable heat, and after running awhile are found sufficiently hot or warm to prevent the full setting of the bonding medium. Such belts have several other disadvantages such as their dependence upon atmospheric temperature (which would vary from day to day), the accumulation of wax thereon, and the great amount of floor space required.

To overcome these handicaps, it has been found necessary in the art to resort to refrigerating systems in order to dissipate the heat from the hot seal as quickly as possible. This, however, increased the initial cost as well as the cost of maintenance and operation of the machine which formerly used long cooling belts, and had a tendency to offset any saving effected by running the machine at a higher rate of speed. As a result, the trade was faced with somewhat of a dilemma as to which type of machine they should buy. If they used a fast operating machine, the initial maintenance and operating cost would be increased; if they used a slower machine, these costs would be lower. Hence, there was great need for a simple belt type cooling device which would seal packages satisfactorily at a high rate of speed yet would be inexpensive to construct, maintain and operate. It is an object of the present invention to provide such a device.

A main object of the present invention is to provide a simple and inexpensive cooling mechanism which will not occupy excessive floor space.

Another object is to provide a hot seal cooling and setting device which will not accumulate wax.

A further object is to provide a simplified and economical seal setting and cooling mechanism which will form a strong neat appearing seal.

2

Another object is to employ a fluid for cooling members engaging with the hot seals of wrapped articles.

Another object is to provide for a succession of cooling devices which will lower the temperature of hot seals rapidly and still be economical to operate and which will occupy only a small amount of floor space.

Other objects and features of the invention 10 will appear as the description of the particular physical embodiment selected to illustrate the invention progresses.

In the accompanying drawings, which form a part of this specification, like characters of reference have been applied to corresponding parts throughout the several views which make up the drawings, in which:

Fig. 1 is a side elevation of a portion of a wrapping machine equipped with the improved cooling mechanism.

Fig. 2 is a plan view of the same.

Fig. 3 is a detail view showing a modified means for cooling the side belts of the mechanism.

Fig. 4 is an end view of a modified means for 25 cooling the side and bottom belts.

Fig. 5 is a sectional side elevation of the same taken from line 5—5 of Fig. 4.

Fig. 6 is a plan view of a modified form of the 30 invention showing vertical side cooling belts arranged in tandem.

The present invention is adapted for use with wrapping machines, particularly bread wrapping machines of the type shown in U. S. Patents Nos. 2,082,945 and 2,133,503, to which reference may 35 be had for further details not herein shown or described. Although particularly adapted for cooling and setting the hot seals of articles wrapped with wax paper, it is also adaptable for use with other thermo plastic coated or heat 40 sealable wrapping materials.

Referring to the drawings, the loaf of bread or article A, which has been completely enfolded in its wrapper during its passage through the machine, is pushed by a pair of pusher arms 45 through the set of end sealer plates 11 and 12, of conventional construction, forming a part of the wrapping machine. The sealer plates 11 and 12 are provided with heating elements 13 for heating them to the proper temperature for fusing 50 together the folded end flaps of the wrapper as

it is pushed past the sealer plates 11 and 12. The bottom sealer plate 14, over which the wrapped articles travel, is provided with a heater element 15 for heating plate 14 to a suitable temperature for heat sealing the bottom seal of the wrapped article.

The articles are successively and continuously delivered by means of successive pairs of pusher arms 10 which are carried by endless traveling chains (not shown) which form a part of the machine. The articles are pushed through the sets of end folder plates 16, 17 and 18, 19 which complete the folding of the end flaps of the wrapper against the package. The folder plates are equipped with heater elements 20 provided to pre-heat the end flaps of the wrapper.

As the packages pass over the heat sealing plate 14 and between the heat sealing plates 11 and 12, the bottom seam and the end folds are heat sealed and fused together. Upon emerging from the heat sealing plates, the seals are still hot and must be held in place and cooled promptly in order to set the seal before it has a chance to open. The bottom seal of a wrapped loaf is frequently made up of only one overlapped seam and presents a simpler sealing problem than does the end seal. The end seal is made up of a large number of creases and overlapped folds. The satisfactory cooling of the end seal has therefore presented a greater cooling problem because of the thickness and air pockets in the end seal. The present invention, however, has provided a solution for these problems. For this purpose there has been provided an endless bottom conveyor belt 21 which may be made of some suitable material such as canvas, and two endless side conveyor belts 22 and 23 which may also be made of similar fabric.

A fabric belt such as canvas is particularly well suited for this purpose because of its ability to absorb moisture until substantially saturated. A three-ply canvas belt operates very well for this purpose because there is a minimum of shrinkage and expansion, and the thickness still permits the belt to absorb and carry a large amount of moisture and still be flexible. Belts of other thicknesses and other absorbent material, however, may also be employed with satisfactory results. These belts serve to hold the seal in place, advance the article, and at the same time cool the seals by dissipating the heat therefrom, particularly by means of absorption, conduction and radiation of the heat from the belt. In order to increase the efficiency of the canvas belts, they are saturated with water so that they will pick up the heat from the hot seal and quickly conduct the same to the exposed surfaces of the belt and thereby allow the heat to escape from the loaf. It is believed that this condition is facilitated by the greater conductivity of a saturated belt over a dry belt. The moisture on the belt forms a closer contact between the hot seal and the belt by eliminating air pockets. Some of the excess moisture evaporates directly from the end of the wrapped article as the cooling belts engage with the seals to be set, and some from the belt, all of which cooperate to give a maximum initial cooling effect so as to set the hot seal at the earliest possible moment.

To obtain the maximum cooling of the belts prior to their engagement with a hot seal, moisture is applied to the belts immediately after they leave the hot seal to allow a maximum heat loss due to evaporation and radiation to take place

on the return run of the belts. Under certain conditions it may be desired to further facilitate and increase the rate of evaporation from belts 22 and 23. In this connection, a conventional fan 79 may be employed to blow a current of air upon the return run of belts 22 and 23. The hot seal cooling and setting efficiency of the belts will thus be maintained when they again engage with the hot seals of other newly sealed articles.

10 A roller 25, which is driven by suitable means (not shown), imparts motion to the belt 21 running over an idler roller 24. The returning lower run of belt 21 contacts and thereby rotates a felt covered moisture applying roller 26 which is 15 partly submerged in water contained in a tank 27. The water tank is carried by a plate 28 supported by uprights 29.

The belts 22 and 23 are suitably driven by pulleys 32 and 33, respectively, and run over idler pulleys 30 and 31. At the terminus of the conveying run of each of the belts 22 and 23 is located a vertically mounted circular brush 34 so positioned as to contact and be rotated by the returning run of each of the belts. Brushes have 25 the advantage of distributing moisture evenly and into all indentations of the belt. The brushes 34 are supported by a holder 35 having upper and lower projecting ears 36 provided with adjustable trunnions 37 on which the brushes 30 rotate. The upper ear of each holder 35 supports a bracket 38 which has a vertical extension 39 supporting a conventional drip valve 40 having means for adjusting the amount of water supplied to the outlet pipe 41 which feeds the brush. 35 The water is supplied from a supply tank 42 having pipes 43 leading to the valves 40. The tank is mounted on a plate 44 and supported by uprights 45, said uprights supporting the bars 46 which serve to carry the holders 35. Each holder 40 35 is equipped with a guard 47 which partly surrounds the brush 34 and serves as a safety means and also as a shield for the water spraying from the brush.

Referring to Fig. 3, a roller 48 having a felt covering 49 may be used in place of the circular brush 34 to apply moisture to the side belts 22 and 23. The wick portion 50 of the felt covering extends beyond the bottom of roller 48 and is partly submerged in the water provided in tank 51. 50 In this manner the wick portion 50 absorbs water and moistens the entire felt covering which contacts and applies moisture to the cooling belts 22 and 23. It will be understood that the rollers 48 will be rotated by the returning run of their respective belts 22 and 23. Roller 48 (as shown in Fig. 3) turns on adjustable trunnions 52 and 53, the former being mounted in a boss 54 of the tank and the other carried by a holder 55 secured to the tank 51.

60 The drip valves, such as 40 (shown in Fig. 1), may also be used in conjunction with rollers 48 to feed water to the upper portions of said rollers to assure a more even distribution of moisture.

65 Referring to Figs. 4 and 5, the side belts 22 and 23 and the bottom belt 21 receive moisture issuing from conventional adjustable spray devices 56 and 57 carried by the U-shaped bracket 58 attached to the machine. Each vertical wall 59 of bracket 58 is equipped with a spray device 56 so positioned as to direct the moisture onto the returning run of the belts 22 and 23. The returning run of the bottom belt 21 receives moisture from a series of spray devices 57 attached to the 70 base of bracket 58, the same being positioned to

direct the moisture over the entire width of the belt 21. A sprayer distributes moisture on the belt evenly and avoids contacting the belt physically, thereby reducing wear and tear upon the belt and moisture applying mechanism.

The water issuing from the spray devices 56 and 57 may be supplied from any suitable source of supply and led to the respective sprayers by pipes 60.

Fig. 6 shows a modified form of the invention wherein a series of side cooling belts 61-64 are arranged in tandem to engage with the hot end seals of newly sealed articles advancing from heat sealing plates which may be similar to those shown in Fig. 2. Each of belts 61-64 passes over conventional drive pulleys 71-74 respectively, and over free pulleys 75-78 respectively, in substantially the same manner as shown in Fig. 2. A horizontal cooling and conveying belt 65 operates in substantially the same manner as belt 21 shown in Fig. 2.

Circular moisture applying brushes 66-69 are positioned adjacent to the belts 61-64 to apply moisture at the beginning of the return run of each belt. Moisture applying pipes 70 furnish each of the brushes with moisture, the amount of which may be regulated by suitable valves, such as 40, shown in Fig. 1. The brushes may be positively rotated by conventional drive pulleys, or may be freely mounted for engagement with the side belts so that they will be rotated by the endless belts 61-64 which are positively driven.

Newly sealed articles are advanced, in the direction indicated by the arrow (Fig. 6), from the heat sealing plates. As the articles are advanced, canvas conveyor and cooling belt 65 cools and sets the bottom seal of the newly wrapped loaf or article. The vertical side belts 61 and 62 engage with the hot end seal and travel therewith to preset and pre-cool the hot seal. These belts remove a large percentage of the heat from the end seal almost immediately upon engagement with the hot seals. This is believed due to the fact that the hotter an object, the more rapid will be its rate of cooling and vice versa. The temperature of belts 61 and 62 will also be comparatively high and as a result they will give off a large quantity of heat on their return runs. This is due to the fact that the greater the difference in temperature between two adjoining masses, the more rapid will be the exchange of heat energy. In the case of belts 61 and 62, the difference in temperature between the surrounding atmosphere and the belts will also be comparatively great and the rate of cooling, therefore, will be very rapid. When the hot seals of the wrapped article or bread loaf come into contact with belts 63 and 64, a large amount of heat will already have been given up, and these belts will act to lower still further the temperature of the hot seal. It is clear that belts 61 and 62 will run with higher temperatures than will belts 63 and 64. Their ability to remove heat will be correspondingly greater because of the great difference in temperature. By dividing the belt up in tandem, the same amount of space will be occupied but the cooling ability will be greater.

The belts 61-64 are all saturated with moisture in substantially the same manner as disclosed in Figs. 1 and 2. The moisture added by brushes 66-69 enables a closer contact to be made between the hot end seal and the side belt. Insulating air pockets between the hot seal and the cooling belt are also avoided. A sufficient quantity of moisture is applied to thoroughly soak the fabric or

canvas belts 61-64 so that their ability to conduct heat away from the hot end seal will be materially increased. On the return run, the moisture is given a chance to evaporate and thereby aid in cooling the belts 61-64. If desired, a blower similar to that shown in Fig. 1 might be employed to increase the rate of evaporation and to increase the cooling of belts 61-64 on their return run.

10 The invention above described may be varied in construction within the scope of the claims, for the particular device selected to illustrate the invention is but one of many concrete embodiments of the same. The invention therefore is 15 not to be restricted to the precise details of the structure shown and described.

What is claimed is:

1. A seal setting device for a wrapping machine in which heat is applied to the seals of a wrapped 20 article to join the overlapped portion thereof comprising, a conveyor for forwarding wrapped articles having hot seals along a predetermined path of travel, a plurality of water absorbent belts arranged in tandem on opposite sides of said conveyor, and means for supplying water to said belts to keep them wet.

2. A seal setting device for a wrapping machine in which heat is applied to the seals of a wrapped article to join the overlapped portion thereof comprising, 25 a horizontal conveyor belt made of a fabric material for forwarding articles bearing hot seals, a moisture applying roller positioned to engage and apply moisture to the return run of said horizontal belt, a pair of fabric belts disposed on opposite sides of said horizontal conveyor belt for engaging the hot end seals of articles and travel therewith for a predetermined distance to pre-cool said seals, means for applying moisture to said fabric belts, a second pair of fabric belts 30 also disposed on opposite sides of said horizontal conveyor for engaging with the pre-cooled seals of said articles and traveling therewith a further predetermined distance to cool the seals still more, and moisture applying means for applying 35 moisture to said second pair of fabric belts.

3. Sealing mechanism for wrapping machines comprising in combination, a conveyor for forwarding wrapped articles having thermo plastic seals along a predetermined path, water absorbent 50 belts extending along said path and engaging said seals, means for supplying water to said belts to keep them wet, and means for blowing a current of air on the moistened portions of said belts to facilitate evaporation from said belts to lower 55 their temperature.

4. In a wrapping machine having devices for forming overlapped end folds on a wrapper folded about the girth of an article and heat sealing said 60 folds, and instrumentalities for advancing the heat sealed packages transversely, the combination with a pair of oppositely disposed endless moisture absorbent fabric conveyor belts each having a vertical operating run traveling in the same direction and at the same speed as the packages conveyed by said instrumentalities and arranged to engage with the heat sealed end folds of the conveyed packages to cool the same, each of said conveyor belts also having a return run disposed out of engagement with the heated 65 sealed package folds, moisture applicators arranged to saturate said belts with moisture at the beginning of their return runs to increase the heat conductivity of said belts along said operating runs and thereby increase the amount of heat

70 absorbed from said heat sealed end folds, means 75

for supplying moisture to said moisture applicators, and means for driving said belts, the extent of said return runs being sufficient to permit the temperature of the return runs of said belts to be substantially reduced by radiation of heat and 5 evaporation of moisture therefrom.
